Atty.

UNITED STATES PATENT OFFICE

JOHANNES WILBERZ, OF HILDEN, GERMANY

METHOD OF AND APPARATUS FOR TRIMMING GRINDING WHEELS

Application filed March 20, 1928, Serial No. 263,180, and in Germany May 18, 1927.

My invention relates to a method of and reciprocation, *g* is a trimming tool which is secured on the frame *c*, and *h* is the workpiece. The grinding wheel *a* is thus arranged intermediate the tool and the workpiece.

5 Means for alternately applying the wheel *a* to the tool *g* and the workpiece *h* by reciprocating the carriage *b* comprise a handle *d*, checks *i* on the frame which permit turning of the handle through an angle not exceeding 180 degs., a shaft *d'* supported in a suitable bearing *c'* of the frame *c*, a circular crank *d''* on the inner end of the shaft *d'*, a crank pin *e* inserted in a slot of the crank and equipped with a square block *e'* to engage between two parallel projections *b'* on the carriage *b*, and a threaded spindle *f* by which the pin *e* is reciprocated in the slot of the crank *d''*.

15 Trimming of grinding wheels is required periodically in order to remove eccentricity due to unequal wear or to maintain a predetermined cross-section of the grinding wheel edge.

20 It has already been suggested to trim grinding wheels on the grinding machine by means of a trimming tool which is applied to the grinding wheel. The diameter of the grinding wheel is reduced by the trimming 70 and in order to make up for this, it is necessary to place the shaft of the grinding wheel nearer to the workpiece. This was effected heretofore either by hand, requiring precision instruments, or by automatic means, requiring 75 electric control. In the former case the personal factor and the accuracy of the measuring instruments play an important part, while in the latter case a complicated and comparatively expensive switching mechanism must be relied on.

80 In the drawings affixed to this specification and forming part thereof an apparatus embodying my invention as applied to a grinding machine is illustrated diagrammatically 85 by way of example.

90 In the drawings

Fig. 1 is an elevation of a grinding machine equipped with my improved apparatus,

95 Fig. 2 is a plan view of the machine, partly in section on the line II-II in Fig. 1.

Referring to the drawings, *a* is a grinding wheel which is rotatably arranged in a carriage *b*, *a'* is a pulley on the shaft of the grinding wheel, *c* is the frame of the machine on which the carriage is arranged for

95 By turning the handle *d* to the left as shown in Fig. 1 until it is arrested by one of the checks *i*, the wheel *a* is withdrawn from the workpiece *h* and applied to the trimming tool *g* and by turning the handle in the opposite direction until it is arrested by the other check *i*, the grinding wheel is withdrawn from the tool *g* and applied to the workpiece *h*. The radius of the crank required for reciprocating the carriage *b* is a function of the gradually decreasing radius of the grinding wheel *a* and may be varied by displacing the pin *e* in the slot of the crank *d''* by means of the spindle *f*. In this manner the radius of the crank, and the stroke of the carriage *b*, are increased as the radius of the grinding wheel decreases. When the 95 grinding wheel has been trimmed, the handle *d* is returned to its initial position as shown in Fig. 1 and the grinding wheel is again in the proper position with respect to the tool.

90 No measuring is required, the personal factor and the accuracy of measuring instruments are eliminated and it is not necessary to rely on the automatic electrical device referred to.

95 I wish it to be understood that I do not desire to be limited to the exact details of method and apparatus described for obvious modifications will occur to a person skilled in the art.

I claim:—

1. An apparatus for trimming grinding wheels comprising a frame, a slide adapted to reciprocate on said frame, a crank carried to rotate in said frame, a crank pin on said crank adapted to impart reciprocation to said slide, means for rotating said crank, means for varying its radius, a grinding wheel on said slide, and a trimming tool arranged on said frame in line with said grinding wheel.

2. An apparatus for trimming grinding wheels comprising a frame, a slide adapted to reciprocate on said frame, a crank carried to rotate in said frame, said crank having a slot, a bracket in said slot, a threaded spindle operatively connected with said bracket so as to vary its position in said slot, a pin on said bracket operatively connected with said slide so as to impart reciprocation thereto upon rotation of said crank, a grinding wheel on said slide, and a trimming tool arranged on said frame in line with said grinding wheel.

25 In testimony whereof I affix my signature.
JOHANNES WILBERZ.
